UNITED STATES PATENT OFFICE.

LEWIS FINE, OF PHILADELPHIA, PENNSYLVANIA, ASSIGNOR, BY MESNE ASSIGNMENTS, TO BUDD WHEEL COMPANY, OF PHILADELPHIA, PENNSYLVANIA, A CORPORATION OF PENNSYLVANIA.

HUB-CAP-LOCKING DEVICE.

Application filed August 27, 1919. Serial No. 320,179.

To all whom it may concern:

Be it known that I, LEWIS FINE, residing at Philadelphia, Philadelphia County, State of Pennsylvania, have invented certain new and useful Improvements in Hub-Cap-Locking Devices, of which I declare the following to be a full, clear, and exact description.

This invention relates to improvements in hub cap locking devices for demountable wheels.

The principal object of my invention is to provide an improved device for locking the hub cap of a demountable wheel, which device shall be more simple and convenient in operation and more nearly "fool-proof" than other devices of this nature with which I am familiar.

Another object of my invention is to provide a locking device for the hub caps of demountable wheels which may be constructed at a low cost, assembled readily and which is particularly adapted to quantity production.

Another object of my invention is to provide a hub cap locking device so constructed as to co-operate with a keeper member on one of the hubs, which keeper member may be formed on the hub easily and cheaply.

Another object of my invention is to provide a hub cap locking device, of the type which is actuated by the application of a wrench to the hub cap, which is adapted to be actuated by a wrench of very simple form and construction.

Further objects, and objects relating to details of construction and economies of production and operation will definitely appear from the detailed description to follow.

In one instance, I accomplish the objects of my invention by the devices and means described in the following specification. My invention is clearly defined and pointed out in the appended claims. A structure constituting a preferred embodiment of my invention is illustrated in the accompanying drawing, forming a part of this specification, in which:

Figure I is a vertical, sectional view through the hub part of a wheel provided with a hub cap locking device embodying my invention.

Figure II is a transverse, sectional view, taken on the line 2—2 of Figure I.

Figure III is a view in end elevation of 55 a hub cap having my improved locking device.

Figure IV is a sectional view through a hub cap similar to that shown in Figure I but showing a locking device in which the 60 latch guide pin is fixed at one side of the center of the hub cap.

Figure V is a view in side elevation of an inner hub and a hub cap equipped with my locking device, the outer hub being 65 shown in dotted lines.

Figure VI is a view similar to Figure V but showing a wrench applied to the hub cap and the latch released.

Figure VII is a transverse, sectional view 70 through a hub cap showing a slightly modified form of locking device in which the latch guide pin is positioned very close to the side wall of the hub cap.

Figure VIII is a transverse, sectional 75 view through said hub cap taken on the line 8—8 of Figure VII.

In the drawings, similar reference numerals refer to similar parts throughout the several views, and the sectional views are 80 taken looking in the direction of the little arrows at the ends of the section lines.

Considering the numbered parts of the drawing, I have shown a demountable wheel including an inner hub 2 mounted on the 85 end of the axle shaft 1 and secured thereto by means of the spline 3 and the axle nut 4. The inner hub has, at its inner end, a radial flange 5 to which the brake drum 6 is fastened by means of the bolts 7. The inner hub has a central flange 8 provided with an external frusto-pyramidal seating surface in which a plurality of slots 9 are formed. The outer end 10 of the inner hub 2 is cylindrical in form and internally 90 threaded at 11. The outer hub 12 is mounted on the inner hub and has an internal frusto-pyramidal seating surface 13 co-operating with the corresponding surface of the flange 8. A pair of keys 14 are fastened 100 to said surface 13, at diametrically opposite points, and positioned within corresponding slots 9, as shown in Figure I. The spokes 15 connecting the hub with the rim are

anchored in suitable seats formed in the outer hub shell. The outer end of the outer hub shell 12 is externally bevelled at 16.

A hub cap 17 has a radial flange 18, extending from it midway between its ends, said flange being internally bevelled and engaging the externally bevelled end 16 of the outer hub shell 12. The inner end 19 of the hub cap is externally threaded and screws in the internally threaded part 11 of the inner hub. The outer end of the inner hub has a plurality of ratchet teeth 20 formed therein, which ratchet teeth extend parallel to the axis of the hub. A slot 21 is formed in the side wall of the hub cap 17 within the flange 18 and the notch 22 is formed in the flange 18 and the portion 30 of the hub cap projecting beyond the flange, said notch 22 being in line with the slot 21. A latch 23 is housed within the hub cap, and lies in a plane at right angles to the axis thereof having a nose 24 extending through the slot 21 and engaging the ratchet teeth 20 on the inner hub. The tail 25 of the latch 23 is slidably mounted on the guide pin 26 which is fastened to the inner face of the hub cap in line with the axis thereof. The compression spring 27 is disposed between the face of the hub cap and the tail 25 of the latch around the guide pin 26. An actuating arm 28 extends from the latch 23, at right angles thereto, and its outer end is disposed in the notch 22 as shown in Figure I. The outer end of the arm 28 has a laterally projecting lug 29 which is adapted to be engaged by the bevelled or cam surface A' of the forked or U-shaped wrench A which is applied to the hub cap to rotate the same. The portion 30 of the hub cap, which projects beyond the flange 18, has a pair of parallel side surfaces 31, which are adapted to be engaged by the wrench A to rotate the hub cap, and the notch 22 is formed in one of said side surfaces, as shown in Figure III.

Figure IV is similar to the corresponding parts shown in Figure I, except that the guide pin 26 is disposed closer to the side wall of the hub cap, and the latch 23 is made correspondingly shorter. The locking device shown in Figures VII and VIII is substantially the same, except that the latch 23' is curved and the guide pin 26' is positioned adjacent the side wall of the hub cap and close to the slot or notch in which the actuating arm 28' works. This construction does not differ substantially from that shown in the other views, but in certain cases where the end of the axle shaft extends a considerable distance within the hub, this affords a larger clearance within the hub cap so as to accommodate the axle nut 4.

From the description of the parts given above, the operation of this device should

be very readily understood. In Figure I, the latch is shown in locking position, being held in position by the spring 27 engaging the tail 25 of the latch. The nose 24 of the latch is guided in the slot 21 and the end of the actuating arm 28 disposed in the notch 22 prevents any tipping or tilting of the latch. The bevel of the nose 24 and of the ratchet teeth 20 is such that the latch yields against the tension of the spring 27 so as to permit the hub cap to be screwed up by hand but any rotation in the opposite direction is effectively prevented by the latch. When it is desired to remove the hub cap, the wrench A is applied to the end portion 30 of the hub cap the parallel arms of the wrench A engaging the sides 31 of such portion of the hub cap in the manner which is well understood in the art. The notch 22 is located in one of said side walls 31 and the lug 29 projects slightly beyond said side wall and will be engaged by the cam surface A' on the arm of the wrench A when said wrench is applied, thus withdrawing the latch nose 24 from the ratchet teeth 20 and permitting the free rotation of the hub cap. It will be apparent that, as soon as the wrench is removed, the latch will snap back into locking position.

I have shown this hub cap locking device applied to a demountable wire wheel, but this invention is not restricted to use in this connection and might be applied with equal facility to demountable wheels of other constructions, or might find utility in other relations.

I am aware that the particular embodiment of my invention, which I have shown and described here, is susceptible of considerable variation without departing from the spirit of my invention, and, therefore, I desire to claim the same broadly, as well as specifically, as indicated by the appended claims.

Having thus described my invention what I claim as new and desire to secure by Letters Patent is:—

1. A device of the class described comprising the combination of a hub cap adapted to be screwed on a relatively fixed hub member, said hub cap having a guide slot in the side wall thereof, a guide pin carried by said cap, both said slot and pin extending parallel to the axis of said hub cap, a latch mounted on said guide pin for reciprocation and having a locking portion extending through said guide slot, and means for reciprocating said latch.

2. A device of the class described comprising the combination of a hub cap adapted to be screwed on a relatively fixed hub member and having a slot in the side wall thereof extending parallel to its axis, and an opening in its end face in line with said slot, a latch lying within said hub cap

in a plane perpendicular to its axis with a locking tongue at one end extending through said slot, and an actuating arm extending from said latch through said opening in the 5 hub cap face.

3. A device of the class described comprising the combination of a hub cap adapted to be screwed on a relatively fixed hub member and provided with a slot 10 formed in the side wall thereof extending parallel to the axis of the hub cap, and an opening in the end face of said hub cap in line with said slot, a guide pin mounted within said hub cap and extending parallel 15 to its axis, a latch slidably mounted on said pin with one end extending through said slot, and an actuating arm extending from said latch through said opening.

4. A device of the class described comprising the combination of a hub cap 20 adapted to be screwed on a relatively fixed hub member and having an outer end with a pair of parallel side faces, one of which has a notch formed therein, a latch recipro- 25 cally mounted in said hub cap and having

an actuating portion lying in said notch, and a lug projecting laterally from the outer end of said portion and adapted to be engaged by a wrench applied to said parallel side faces.

5. A device of the class described comprising a hub cap adapted to be screwed on a relatively fixed hub member and having a radially extending flange provided with a bevelled edge, adapted to engage the end of a removable hub mounted on said fixed hub member, and a wrench-engaging portion in front of said flange and having parallel sides, and a latch slidably mounted in said hub cap to reciprocate parallel to the axis 40 thereof, an actuating arm extending from said latch through said flange and having an actuating finger positioned adjacent one of the parallel sides of said wrench-engaging portion to be engaged to retract the latch by 45 the application of a wrench to said wrench-engaging portion.

In testimony whereof, I affix my signature.

LEWIS FINE.
